CLAIM

I claim the ornamental design for a skincare device, as shown and described.

DESCRIPTION

FIG. 1 is a perspective view of a skincare device.

FIG. 2 is a top view of the skincare device.

FIG. 3 is a bottom view of the skincare device.

FIG. 4 is a rear view of skincare device.

FIG. 5 is a front view of the skincare device.

FIG. 6 is a right side view of the skincare device; and,

FIG. 7 is a left side view of the skincare device.

The dashed lines in the figures illustrate the portions of the design that form no part of the claimed design. None of the broken lines form any part of the claimed design.
